PHOTOGRAPHIC COPYING MACHINE

Helmut Riffert, Zetel, and Alfons Boothby, Wilhelms-haven, Germany, assignors to Olympia Werke A.G., Wilhelmshaven, Germany

Filed June 25, 1965, Ser. No. 85,906

Term of patent 14 years

(Cl. D61—1)

FIG. 1 is a front perspective view of a photographic copying machine showing our new design;

FIG. 2 is a side perspective view thereof; and

FIG. 3 is a rear perspective view thereof.

We claim:

The ornamental design for a photographic copying machine, substantially as shown.
